(57) CLAIM

The ornamental design for a rollaway bed cover, as shown and described.

DESCRIPTION

FIG. 1 is a rear, left, and top perspective view of a rollaway bed cover, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area labeled 8 in FIG. 1 comprising an adjusting buckle.

The broken lines shown in the drawings are included for the purpose of illustrating portions of the rollaway bed cover that form no part of the claimed design.
